SAMUEL G. RICE, OF ALBANY, NEW YORK.

Letters Patent No. 90,391, dated May 25, 1869.

IMPROVED WASHING-MACHINE.

The Schedule referred to in these Letters Patent and making part of the same.

To all whom it may concern:

Be it known that I, SAMUEL G. RICE, of the city and county of Albany, in the State of New York, have invented a new and improved Washing-Machine; and I do hereby declare that the following is a full, clear, and exact description thereof, reference being had to the accompanying drawings, making part of this specification, in which—

Figure 1 is a perspective view of the machine complete, with the cover raised to expose the slatted drum.

Figure 2 is a longitudinal section, taken centrally through the machine, in the vertical plane indicated by red line $x x$ in fig. 3.

Figure 3 is a section taken horizontally through the machine, in the plane indicated by red line $y y$, in fig. 2.

Similar letters of reference indicate corresponding parts in the several figures.

The object of this invention is to employ a rotary slatted drum, which is adapted for receiving fabrics to be washed within it, and which is constructed with slats, that present rounded rubbing-surfaces to the fabrics while being washed, and flat surfaces to the water, and to combine with such drum a swivel compressor, which is arranged upon a central shaft in the drum, and so constructed that it will operate to press the fabrics outwardly against the rubbing-surfaces of the slats, and to prevent the fabrics from gathering into a ball, as will be hereinafter explained.

To enable others skilled in the art to understand my invention, I will describe its construction and operation.

In the accompanying drawings, A represents the wash-box, which is mounted upon legs C C, provided with a hinged cover, B, and constructed with a concave bottom.

Within this box A is a slatted drum, consisting of solid circular heads D D, and fixed slats $a a'$, which slats are constructed with their inner edges rounded and their outer edges sharp, thus presenting flat sides to the water, for directing it forcibly toward the centre of the drum, as this drum is rotated in the direction indicated by the arrows in fig. 2.

The slats are arranged tangential to a circle described within the circumference of the heads, and, as the drum is rotated, their knife-edge form allows them to cut through the water freely, and direct the currents inwardly through the fabrics contained in the drum, and against the blades g of arms G, which are placed loosely upon a central shaft, E.

The slats a are applied to and secured between two segments, F, which are hinged, at b, to the heads D, and constitute a door for closing the opening through which the fabrics are introduced into and removed from the drum.

The buttons p will keep said slatted door shut.

The shaft E is arranged in the centre of the drum, and secured to its heads, and upon this shaft arms G G are loosely placed, which are connected by blades $g g$, placed obliquely to the axis of shaft E.

The arms G, and their blades g , constitute what I shall denominate a compressor, which serves a twofold purpose, to wit, it separates the fabrics in the drum, and prevents them from gathering into a ball or roll, and it also operates to keep the fabrics against the rounded rubbing-surfaces of the slats $a a'$, during the washing or cleansing-operation.

This compressor will also interrupt the currents of water which are forcibly directed into the drum by the slats $a a'$, and thereby assist in the cleansing-operation.

The drum is centrally hung, by the bearing h , on one side, and by a crank-shaft, j, applied on the opposite side.

The bearing h is flanged, and reduced at its inner end, i, and secured, by its flange, to the box A, as shown in fig. 3.

The shaft j carries a crank, J, on one end, and its opposite end is made square, and fitted into a square socket made in a plate, n, which is secured centrally to the drum, as shown in fig. 3.

The plate k , placed outside of the box A, and secured to it, receives through it the cylindrical portion of the shaft j .

I do not confine myself to this mode of hanging the drum in the box A, as other well-known plans adapted for this purpose may be used.

Having described my invention,

What I claim as new, and desire to secure by Letters Patent, is—

1. The arrangement of a compressor, G g, loosely within a slatted drum, so as to operate substantially as described.

2. The double-bevelled and rounded-edge blades or slats a , arranged around a swivelling blade, g , substantially as described.

SAMUEL G. RICE.
